UNITED STATES PATENT OFFICE.

ANTHONY ODENING, OF CALUMET, MICHIGAN.

RAIN-ALARM.

1,270,652.

Specification of Letters Patent. Patented June 25, 1918.

Application filed January 3, 1918. Serial No. 210,175.

To all whom it may concern:

Be it known that I, ANTHONY ODENING, a citizen of the United States, residing at Calumet, in the county of Houghton and

5 State of Michigan, have invented certain new and useful Improvements in Rain-Alarms; and I do hereby declare the following to be a full, clear, and exact description of the invention, such as will enable 10 others skilled in the art to which it appertains to make and use the same.

This invention relates to signals and more particularly to rain signals and the primary object of the invention is to provide an improved device to be placed out of a window for giving an audible alarm when it begins raining, so the attention of persons in the house will be called to the fact so that the windows can be fixed accordingly.

20 A further object of the invention is to provide an improved device of the above character, which is durable and efficient in use, one that is simple and easy to manufacture, and one that can be placed upon the market 25 at a reasonable price.

With these and other objects in view, the invention consists in the novel construction, arrangement and formation of parts, as will be hereinafter more specifically described, 30 claimed and illustrated in the accompanying drawing, forming a part thereof, in which:—

Figure 1 is a plan view of the improved rain alarm,

Fig. 2 is a vertical section through the improved rain alarm, and

Fig. 3 is a fragmentary plan view of the arbor and alarm mechanism removed from the casing.

Referring to the drawing in detail, where- 40 in similar reference numerals designate corresponding parts throughout the several views, the numeral 1 generally indicates the improved rain alarm which includes the protecting housing 2, which may be of any 45 preferred form or shape. The housing 2 has a removable lower wall 3 whereby the interior mechanism of the device can be readily disclosed so that the same can be readily fixed, if the same becomes out of order, and 50 the rear wall 3 carries a plurality of supporting legs 4, whereby the same is held in an upright position. Secured on the upper wall of the casing is an outwardly extending arm 5, which has its free outer end enlarged 55 as at 6 and provided with an opening 7 which detachably supports the tube 8, which

has its upper end flared as at 9 to provide a funnel shaped member, for a purpose which will hereinafter more fully appear.

Secured to the casing 2 in the ordinary or 60 any preferred manner is the supporting arbor 10, which supports the clock mechanism 11 for sounding the alarm bell 12 carried by the casing and extending exteriorly of the same. The mechanism 11 is of the general 65 type used in the ordinary alarm mechanism for alarm clocks and includes the coil spring 13 having one end secured to the shaft 14, which has its ends journaled in the arbor and its opposite end to the spring housing 15, 70 which is regulated by the ordinary ratchet mechanism 16. A key 17 is removably secured to the end of the shaft 14 and protrudes out of the rear wall 3 so that the shaft may be rotated to wind up the spring 13. The 75 shaft 14 has keyed thereto in the ordinary manner the relatively large gear 18 which meshes with a relatively small gear 19 keyed on the shaft 20 which has its opposite ends journaled in the arbor. Keyed to the shaft 20 80 immediately above the relatively small gear 19 is an escapement wheel 21, which is engaged by the oscillating lever 22, which is keyed to the shaft 23, which is journaled in the arbor, and this oscillating arm has the 85 ordinary double ratchet 23 for engaging the escapement wheel, and when the spring is released the escapement wheel 21 is rotated, and the lever 22 oscillated. The outer end of the lever carries the clapper 24, which ex- 90 tends through an aperture 25 in the casing and is adapted to strike the bell 12. The shaft 23 has rigidly secured thereto above the arm 22, the outwardly extending arm 26, which is disposed in the path of the down- 95 turned end 27 of a spring arm 28 which is secured to the arbor at its rear end as at 29. The spring lever normally tends to hold the downturned arm 27 in the path of the arm 26 and thus prevent movement of the same 100 and thereby prevent the oscillation of the clapper 24. Pivotal secured to the arbor 10 by means of a pivot pin 30, which extends through a pair of ears 31 is an operating lever 32. The lever is pivotally sup- 105 ported intermediate its ends by the pivot pin 30 and has the free end of its short arm secured to the downturned end 27 of the spring lever 28. The free end of the long end of the operating lever 32 is provided 110 with a cup-shaped member 33, which is disposed in the tubular member 8. The tu-

bular member 8 is provided with a vertical slot 34 through which the long arm of the operating lever 32 extends.

In the operation of the improved device, 5 a piece of tissue paper 35 is placed over the funnel 9 and held in position by means of an elastic band 36 and a weight 37 is placed upon the tissue paper. Thus the device is ready for operation and the same is 10 placed out of a window or other suitable and desired place and as soon as the first few drops of rain strike the tissue paper 35 the same will become weakened and the weight 37 will tear its way through the 15 paper and drop on the cup 33, which will rock the lever 32 on its pivot 30 and raise the downturned arm 27 of the spring lever 28 from out of the path of the arm 26 rigidly carried by the shaft 23, which will allow the 20 lever 22 to oscillate and the clapper 24 to engage the bell 12 and ring the same. A circular housing 38 is secured to the upper wall of the casing 2 and provides means for receiving the weight, when the same is 25 not in use. When the rain storm is over, the weight 37 is removed from the cup-shaped member 33 and a new piece of tissue paper 35 is provided and placed on the funnel and the weight is then placed in position and 30 the device is ready for another operation.

From the foregoing description it can be seen that an improved device is provided for giving an audible signal when it begins to rain, which will operate as soon as the 35 first few drops of rain hit the same, thus making the device an efficient and ready warning.

In practice, I have found that the form of my invention, illustrated in the accompanying drawing and referred to in the above description, as the preferred embodiment, is the most efficient and practical; yet realizing the conditions concurrent with the adoption of my device will necessarily vary, I desire 45 to emphasize the fact that various minor changes in details of construction, proportion and arrangement of parts may be re-

sorted to, when required without sacrificing any of the advantages of my invention as set forth.

50

What I claim as new is:—

1. A rain signal comprising an alarm mechanism, a trip for actuating the alarm, a tissue paper partition supported above the trip, and a weight resting upon said paper, 55 as and for the purpose specified.

2. A rain signal comprising an alarm mechanism, a trip for actuating the alarm, a removable and replaceable tissue paper partition supported above the trip, and a weight 60 resting upon said paper, as and for the purpose specified.

3. A rain signal comprising a casing, an alarm mechanism in the casing, a pivoted trip lever for actuating the alarm mechanism, a funnel carried by the casing and receiving the free end of the trip lever, relatively thin paper positioned across the top of the funnel, and a weight resting upon 65 said paper.

4. A rain signal comprising a casing, a spring alarm mechanism arranged in the casing, a bell, a clapper carried by the spring alarm mechanism for engaging the bell, a resilient arm engaging the clapper to prevent movement thereof, an operating lever pivoted in the casing and extending outward of the same, means operatively connecting the inner end of the operating lever with the resilient arm, a cup-shaped member carried by the outer end of the arm, a funnel secured to the casing and receiving the free end of the arm and the cup-shaped member, a tissue paper partition arranged over the funnel, means detachably holding the tissue 85 paper in position, and a weight resting upon said tissue paper, as and for the purpose specified.

In testimony whereof I affix my signature in presence of two witnesses.

ANTHONY ODENING.
